UNITED STATES PATENT OFFICE

162,639

ADJUSTABLE FLUORESCENT LAMP

Irving Fiori, Chicago, Ill., assignor to Art Specialty Co., Chicago, Ill., a corporation of Illinois

Application April 5, 1950, Serial No. 8,978

Term of patent 14 years

(Cl. D48—20)

To all whom it may concern:

Be it known that I, Irving Fiori, a citizen of the United States, residing at Chicago, in the county of Cook and State of Illinois, have invented a new, original, and ornamental Design for Adjustable Fluorescent Lamp, of which the following is a specification, reference being had to the accompanying drawing, forming a part thereof.

In the drawing—

Fig. 1 is a side elevational view of an adjustable fluorescent lamp showing my new design;

Fig. 2 is a front elevational view thereof;

Fig. 3 is a top plan view thereof;

Fig. 4 is an enlarged fragmentary perspective view thereof; and

Fig. 5 is an enlarged fragmentary rear perspective view of the base and the lower pivoted arm supporting member.

The dominant features of my design are shown in solid lines.

I claim:

The ornamental design for an adjustable fluorescent lamp, as shown and described.

IRVING FIORI.
